UNITED STATES PATENT OFFICE.

WILLIAM KAISLING, OF CHICAGO, ILLINOIS, ASSIGNOR TO FRANK B. COOK, OF CHICAGO, ILLINOIS.

PROTECTIVE APPARATUS FOR SWITCHBOARDS AND THE LIKE.

No. 904,486.

Specification of Letters Patent.

Patented Nov. 17, 1908.

Application filed October 5, 1903. Serial No. 175,788.

To all whom it may concern:

Be it known that I, WILLIAM KAISLING, a citizen of the United States, residing at Chicago, in the county of Cook and State of Illinois, have invented certain new and useful Improvements in Protective Apparatus for Switchboards and the Like, of which the following is a specification.

This invention relates to devices to guard against the more or less deleterious effects of what are known as "sneak currents" upon sensitive and delicate electric instruments, such as telephone-switchboard apparatus and the like, at the interior terminals 15 of electric circuits. As is well known, there are various sources and kinds of abnormal currents, the action of which may temporarily or permanently destroy the usefulness of such instruments, this invention having to do only with means for arresting and dissipating foreign currents of low potential, which are known as "sneak currents".

There are many forms of so-called "heat coil" or thermal arresters for this purpose, 25 many of which, while accomplishing the object for which they are intended, are objectionable on account of a more or less complex construction, and because, in most instances, they are self-destructive in operation and useless thereafter, or, at best, must be made the subject of considerable manipulation or repair to put them in condition for further useful work.

The particular object of the present invention is the production of a simple, efficient and substantially indestructible heat-coil or thermal arrester, which may be said to be self-repairing after operation, the mere reversal of the coil putting the device 40 again in condition to fulfill its function.

This invention contemplates the usual line and switchboard circuits, with any usual connections, preferably provided with the usual means for protecting the switchboard-circuit against lightning and other high potential charges or discharges, each line branch of said circuit including a coil or other resistance adapted to become heated when a certain fixed maximum of intensity 45 or strength of current flows therethrough, the heat being utilized to fuse some metal—such as solder, some forms of which flow readily at a comparatively low temperature—which has served to bind together two 50 members, one of which is under spring-

pressure and which, when released by the melting of the solder, is capable of movement with relation to the other or supporting member to open the circuit and ground the same to dissipate the foreign 60 current, which has been or may become the cause of trouble.

This invention seeks to avoid disadvantages usually attendant upon the melting of the solder in other devices of this class, 65 which, in some forms, permits of a complete separation of the members or, possibly, a partial destruction of the device, rendering it useless until replaced or repaired. My invention further contemplates, therefore, a 70 construction and arrangement which obviates the necessity of repairing or substitution, and one in which the line circuit is opened not in the coil but exterior thereof and by mechanical means.

With these and other ends in view, the invention consists, generally, in an electric circuit having one or more interposed conductors each comprising a resistance in close proximity to an insulated supporting member 80 to which is normally secured by fusible material a spring-pressed operating member, the latter being adapted upon its release to engage or impinge against a spring contact to open said circuit and, preferably, to 85 ground the same.

My invention further consists in means for making my protective device reversible and again operable without repairing.

My invention further consists in the novel 90 means for opening the line circuit and simultaneously a secondary or alarm circuit. And my invention further consists in the various other details of construction, location, arrangement, electrical connection and 95 combinations of parts, all as hereinafter described and particularly pointed out in the claims.

My invention will be more readily understood by reference to the accompanying 100 drawings, forming a part of this specification, and in which

Figure 1 is a central sectional elevation of a device embodying my invention. Fig. 2 is a top plan view thereof. Fig. 3 is an 105 enlarged central section of one of the coils and its supports. Fig. 4 is a bottom plan view thereof.

Referring now to the drawings in detail, 110 numeral 2 refers to a portion of the elongated

plate or bar which usually forms a part of the frame work of the distributing frame through which the wires entering a telephone central office are connected before the circuits terminate at the switchboard, or it may be a part of a terminal head or some apparatus on which protective devices are adapted to be mounted. Suitably attached to the plate or bar 2 are the grounding plates 3, carrying the carbons 4 and the interposed insulating substance 5, a common form of lightning arrester which forms no part of the present invention.

Mounted upon the plate 2, supported and separated by suitable strips of insulation 6, are two sets or series of spring terminals, conductor-supports or contacts, which include the terminals 7 and 8 on one side of said plate for the line wires *a* and *b*, respectively, and the terminals 9 and 10 on the other side of said plate for the switchboard wires *c* and *d*, respectively. The terminal 7 extends through said insulating supports 6 and is in spring-pressed contact with the strip 11, between which and the strip 12 the coil C is removably mounted, as hereinafter described. A conductor 13 connects the strip 12 with the terminal 9 for the wire *c* to the switchboard.

The terminal 8 for the line wire *b* is electrically connected through the conductor 14 with the spring conductor 15, similar in all other respects to the extension 7' of the terminal 7, normally contacting with the insulated strip 16, between which and the extension 10' of the terminal 10 for the switchboard wire *d* the coil C' is similarly mounted.

As illustrated in the drawings, each of the coils C and C' may comprise a preferably copper spool 17 supported between two heads 18 and 18', of insulating material, surmounted at each end by the preferably brass caps 19 and 19'. A suitable coil of insulated wire 20 about the spool 17 connects the two caps 19 and 19', which preferably embrace the cylindrical insulating casing 21. Extending centrally through the whole coil and projecting beyond the heads 18 and 18' at each end is a preferably brass pin 22 which is soldered in operative position to and within the spool 17 with what is known as "easy flowing" solder, or solder which will fuse at from 160° to 170°, Fahrenheit. It will be noticed that projections 23 and 23' of the heads 18 and 18' through the caps 19 and 19' and the supporting strips protect the pin 22 at both ends from contact with said supporting strips, which are, however, in electrical contact with said caps 19 and 19'.

The pins 22, in both the coil C and the coil C', are designed to be constantly under spring pressure, which I provide by means of insulated spring strips 24 and 25, respectively. In Fig. 1 I have shown the relative

positions of pin and coil, for the coil C prior to and for the coil C' after operation, in the coil C, the pin being withheld against movement under action of the spring by the fusible material which joins pin and spool. Upon release of said pin, as hereinafter described, it is capable of a limited longitudinal movement through said spool and coil, said movement being checked at a point where the lengths of projections at opposite ends have been reversed, whereby, pin and spool becoming reunited through cooling of the solder, the entire coil may be removed for a repetition of the operation.

Proceeding now to trace the circuits, it will be noted that the current from the line wire *a* will enter through the terminal 7, passing, successively, through the spring extension 7' thereof, the insulated strip 11, the cap 19 of the coil C, the resistance coil 20, the cap 19', the strip 12, the connecting conductor 13, the terminal 9 and the wire *c* to the switchboard; returning through the wire *d*, the terminal 10, the extension 10' thereof, the coil C' in a similar manner, the insulated strip 16, the spring contact strip 15—when the pin 22 of the coil C' is in its normal position (as indicated in Fig. 1 for the coil C), in which position the strip 15 is in contact with the insulated strip 16—the conductor 14, and the terminal 8 to the other line wire *b*.

Under ordinary conditions, and with the ordinary currents which the device is adapted to handle, the normal adjustment of the coil and pin is not effected. Abnormal currents, not provided for by the usual fuses and the lightning arrester, will heat the resistance coil 20 and consequently the spool 17, and will, in from twenty-five to thirty seconds, fuse the solder which unites the pin and spool, permitting of a free longitudinal movement of said pin within said spool. The pin being constantly under spring pressure through the spring conductor 24 (or 25 for the coil C'), said spring will, immediately upon release of said pin, overcome the lesser spring pressure of the spring contact 7', breaking the circuit exterior of the coil C and grounding said strip 7' through the extension plate 3 and the bar 2, as is shown in that portion of Fig. 1 illustrating the relative positions of the pin in the coil C'. It will be apparent that when this circuit is broken, the heated spool 17 will quickly cool and the solder again harden and unite pin and spool, the channel between pin and spool being so small that capillary attraction will prevent the escape of the molten solder. The length of this pin is such that the portion which projects out of the head of the coil at one end, in its normal condition, is the same as the length of the projection at the other end of the coil after operation thereof. Therefore, when the spool has

125
130

cooled and the solder again hardened to join the two members, it is only necessary to remove, reverse and replace the coil, when it is again ready to serve its function. To facilitate removal and reversal of the coil, I have shown, as best illustrated in Fig. 4, the supporting strip 12 (or 10' for the other coil) slotted at its extremity, and the strip 11 (or 16 for the opposite coil) provided 10 with a somewhat elongated aperture.

I may further equip my device, if I desire, with any usual form of alarm or signal, which may comprise, for the purposes of this description, a vibrating bell in circuit 15 with a battery 27, or other source of electric energy, between the contact strip 25 and the ground wire *f*, whereby, upon grounding of the contact 15, a circuit is closed from the ground through the wire *f*, the bell-operating magnets, the battery 27, the spring conductor 25, the pin 22 within the coil C', the spring contact 15, the extension plate 3, and the bar 2 to the ground. It is thus apparent 20 that the same operation which opens and 25 grounds the primary or main circuit, simultaneously closes the secondary or alarm circuit, ringing the bell or operating other form of signal to notify the attendant in charge of the presence of the foreign cur- 30 rent.

The function of the insulated coil of wire 20 around the spool 17 is, obviously, to provide a known resistance which will generate the heat necessary to melt the solder and 35 permit of the free movement of the pin 22 within said spool. I do not desire to be limited to this particular form of resistance, as it is apparent that I may employ a carbon sleeve or other type of resistance without departing from the spirit of my invention.

Many modifications of other minor details of the apparatus will also doubtless readily suggest themselves to those skilled in the art 45 to which it appertains and I therefore do not desire to limit my invention to the specific construction herein shown and described.

Having thus described my invention, I claim as new and desire to secure by Letters 50 Patent:

1. A heat coil arrester having a body and a circuit breaker operating member extending through and longer than the body, with means to move said members upon each other 55 in operation, whereby the device is reversible after each operation.

2. A heat coil arrester having a body and a mechanical circuit breaking member heat controlled, extending completely through 60 the body and of greater length than the same, with means to force a relative movement of the body and the circuit breaking member under the influence of undue heat whereby the device is reversible after each 65 operation thereof.

3. A thermal arrester having a resistance, a supporting member, and a circuit breaker operating member normally secured by fusible material to said supporting member, the whole being inclosed within a suitable casing 70 shorter than the said operating member, the ends of the latter alternately projecting therefrom after successive operations, whereby the device is reversible.

4. In an electric system, a circuit and a reversible heat-coil arrester comprising a heating element connected in the circuit and a circuit-controlling element extending through, longer than, and under the control of the heating element, but itself external 80 to the circuit.

5. In combination, an electric circuit and a removable heat-coil arrester having the circuit-breaker operating member exterior of said circuit and extending completely 85 through said coil and its casing, whereby the device is reversible after each operation thereof.

6. The combination, with a main circuit and a secondary alarm circuit, of a heat- 90 coil arrester having the circuit-breaker operating member exterior of said main circuit and in said secondary circuit.

7. The combination, with a main circuit and a secondary alarm circuit, of a reversible circuit-breaker operating member exterior of said main circuit and in said secondary circuit.

8. The combination, with a main circuit and a secondary alarm circuit, of a removable 100 thermal arrester having the circuit-breaker operating member exterior of said main circuit and in said secondary circuit, said member extending completely through the device whereby the same is reversible 105 after each operation thereof.

9. In combination, an electric circuit, two coöperating members joined by fusible material and exterior of said circuit, means for exerting yielding pressure tending to change 110 the relative positions of said members, a resistance in said circuit and in proximity to said fusible material, and a spring contact located to be engaged and opened by movement of one of said members.

10. The combination, with a normally closed main circuit and a normally open secondary alarm circuit, of two coöperating members joined by fusible material and exterior of said main circuit, means for exerting a constant pressure tending to change 120 the relative positions of said members, a resistance in said main circuit in proximity to said fusible material, and a spring contact located to be operated by movement of one 125 of said members to open said main circuit and close said secondary circuit.

11. In combination, an electric circuit, two coöperating members joined by fusible material and exterior of said circuit, one of said 130

members being stationary and the other under spring pressure, a resistance in said circuit and in proximity to the fusible joint, and a spring contact in said circuit located to be engaged by the spring-pressed member when released.

12. The combination, with a normally closed line circuit and a normally open alarm circuit, of two members joined by fusible material in said alarm circuit and exterior of said line circuit, one of said members being stationary and the other under spring-pressure, a resistance in said line circuit in proximity to the fusible joint, and a spring contact in said line circuit located to be engaged by said spring-pressed member when released to open said line circuit and close said alarm circuit.

13. In combination, an electric circuit, two coöperating members joined by fusible material and exterior of said circuit, means for exerting yielding pressure tending to change the relative positions of said members, a resistance in said circuit and in proximity to said fusible material, and a spring contact located to be engaged and opened by movement of one of said members, said resistance and both of said members constituting a detachable device reversible after each operation for a repetition thereof.

14. The combination, with a normally closed main circuit and a normally open secondary alarm circuit, of two coöperating members joined by fusible material and exterior of said main circuit, means for exerting a constant pressure tending to change the relative positions of said members, a resistance in said main circuit in proximity to said fusible material, and a spring contact located to be operated by movement of one of said members to open said main circuit and close said secondary circuit, said resistance and both of said members constituting a detachable device reversible after each operation for a repetition thereof.

15. In combination, an electric circuit, two coöperating members joined by fusible material and exterior of said circuit, one of said members being stationary and the other under spring pressure, a resistance in said circuit and in proximity to the fusible joint, and a spring contact in said circuit located to be engaged by the spring-pressed member when released, said resistance and both of said members constituting a detachable device reversible after each operation for a repetition thereof.

16. The combination, with a normally closed line circuit and a normally open alarm circuit, of two members joined by fusible material in said alarm circuit and exterior of said line circuit, one of said members being stationary and the other under spring-pressure, a resistance in said line circuit in proximity to the fusible joint, and

a spring contact in said line circuit located to be engaged by said spring-pressed member when released to open said line circuit and close said alarm circuit.

17. A thermal arrester comprising a sleeve, a pin within said sleeve and normally secured thereto by fusible material, a resistance in proximity to said sleeve and included in the circuit to be protected, and a circuit controller with means for reversibly receiving the pin and associated parts.

18. A thermal arrester comprising a sleeve, reversible supporting means therefor, a pin within said sleeve having free projecting extremities, said pin being normally secured to said sleeve by fusible material and when released operable in either direction, and a resistance in proximity to said sleeve.

19. The combination with an electric circuit, of a stationary sleeve, an insulated support for receiving the sleeve, a pin normally secured in one position within said sleeve by fusible material, a resistance in said circuit in proximity to the sleeve, and a circuit-breaking device included in the circuit and controlled by the position of the pin relatively to the sleeve.

20. The combination with an electric circuit, of a stationary sleeve, insulating supporting means adapted to receive and hold the sleeve, a spring pressed pin normally secured within said sleeve and fixed thereto by fusible material, said pin extending through and being longer than the sleeve, so as to project therefrom, together with a heat generating resistance in the circuit and surrounding the said sleeve.

21. In combination, a stationary sleeve, insulating supports therefor, a casing with said supports completely inclosing said sleeve, a pin within said sleeve and normally secured thereto by fusible material, and heat-generating resistance in proximity to said sleeve.

22. The combination with a main circuit and a secondary alarm circuit, of a removable thermal arrester having a body with a heating device included in the main circuit and a circuit breaker operating member in the secondary circuit, said member extending through and being longer than the body of the device and adapted to be moved relatively thereto so that each end will project alternately after successive operations, and will remain in that position upon cooling, whereby the said arrester is reversible.

23. The combination with an electric circuit, of a heat coil arrester comprising the following instrumentalities: A sleeve with a heating resistance included directly in the circuit, a pin normally secured rigidly in and to said sleeve by fusible material, said pin being longer than the sleeve, means controlling the circuit and normally obstructed

to prevent operation by the conjoined action of pin and sleeve and permitted to act when the latter are freed from each other by undue heat, whereby after the circuit 5 is broken it may again be put into operative condition by merely reversing the arrester.

24. The combination with a spring circuit breaker, of a reversible heat coil arrester comprising the following instrumentalities:

10 A casing, an insulated heating member, a sleeve and a pin extending through the sleeve and normally secured thereto by fusible material, said pin being longer than the casing, the arrangement being such that the pin can be moved relatively to the sleeve in one direction or the other when released by undue heat, and will retain its changed position after each operation, whereby the same arrester may be used for a number of 15 operations.

25. The combination, with a normally closed main circuit and a normally open secondary alarm circuit, of a stationary sleeve, insulating supports therefor, a spring-pressed pin exterior of said main circuit and in said secondary circuit normally secured within said sleeve by fusible material, a resistance in said main circuit in proximity to said fusible material, and a spring, contact located to be operated by movement of said pin to open said main circuit and close said secondary circuit, said pin projecting through both of said supports whereby the device is reversible after operation for a 30 repetition thereof.

26. The combination, with an electric circuit, of an insulated supporting member, a resistance in said circuit in proximity thereto, a spring-pressed operating member normally secured to said supporting member by fusible material and operable longitudinally in either direction, and a spring contact in said circuit in the path of movement of said operating member.

45 27. The combination, with a normally closed main circuit and a normally open secondary alarm circuit, of an insulated supporting member, a resistance in said circuit in proximity thereto, a spring-pressed operating member exterior of said main circuit and in said secondary circuit, normally secured to said supporting member by fusible material and operable longitudinally therethrough in either direction, and a spring contact in the path of movement of said operating member adapted to open said main circuit and close said secondary circuit.

60 28. In combination, a suitable casing, a sleeve supported therein by insulating material, a pin extending completely through said sleeve and casing and normally secured to said sleeve by fusible material, means for subjecting said pin to yielding pressure, an electric circuit, a spring contact therein and

in the path of movement of said pin, and a 65 resistance in said circuit in close proximity to said sleeve.

29. The combination, with an electric circuit including at least one of a pair of spring supports, an incased resistance removably supported therebetween, and a spring contact, of an insulated supporting member in proximity to said resistance, and a spring-pressed member normally secured to said supporting member by fusible material and 70 adapted upon release to engage said spring contact, said resistance, supporting member and operating member constituting a detachable device capable of reversal after each operation for a repetition thereof. 80

30. The combination, with a normally closed main circuit including at least one of a pair of spring supports, an incased resistance removably supported therebetween, a spring contact, and a normally open secondary alarm circuit, of an insulated supporting member in proximity to said resistance, a spring-pressed member in said alarm circuit normally secured to said supporting member by fusible material and adapted upon release 85 to engage said contact to open said main circuit and close said secondary circuit, said resistance, supporting member and operating member constituting a detachable device capable of reversal after each operation for 90 a repetition thereof.

31. A self-soldering heat-coil arrester comprising a body and a central spindle normally secured together by fusible material, circuit-closing means engaged respectively 100 by the body and pin in operation, said circuit closing means permitting cooling of the device in operative condition after each actuation, whereby the members will again become rigidly connected, and the device is 105 ready for further use at once.

32. A heat-coil cartridge comprising a body portion having a heating conductor associated therewith, projecting portions for the ends of said body portion, said projections being connected to move together relatively to said body portion, and fusible material in proximity to said heating conductor, normally holding said projecting portions against movement. 110

33. A heat coil cartridge comprising a spool, a heating conductor for said spool, a pin passing through the spool and adapted to project at either end thereof, and fusible material fastening said pin to the spool. 115 120

In testimony of the foregoing I have hereunto set my hand in the presence of two witnesses.

WILLIAM KAISLING.
